CLAIM

The ornamental design for a wireless communication device, as shown and described.

DESCRIPTION

FIG. 1 is a perspective view of an ornamental design of a wireless communication device showing our new design.

FIG. 2 is a rear orthographic view thereof.

FIG. 3 is a front orthographic view thereof.

FIG. 4 is a left side orthographic view thereof.

FIG. 5 is a right side orthographic view thereof.

FIG. 6 is a top orthographic view thereof.

FIG. 7 is a bottom orthographic view thereof.

FIG. 8 is a perspective view of an ornamental design of a second embodiment of a wireless communication device showing our new design.

FIG. 9 is a rear orthographic view thereof.

FIG. 10 is a front orthographic view thereof.

FIG. 11 is a left side orthographic view thereof.

FIG. 12 is a right side orthographic view thereof.

FIG. 13 is a top orthographic view thereof; and,

FIG. 14 is a bottom orthographic view thereof.

The broken lines shown in FIGS. 1-7 are included for the purpose of illustrating environmental elements only and form no part of the claimed design.

1 Claim, 8 Drawing Sheets
